HEAT TRANSFER DEVICE

James Anderson and Carl Arsen Klobassa, Dallas, Tex.,
assignors to Continental Electronics Manufacturing
Company, Dallas, Tex., a corporation of Texas
Filed Nov. 20, 1963, Ser. No. 324,954
6 Claims. (Cl. 317—100)

The present invention relates to a heat transfer device, and, in particular, to apparatus for cooling a radio frequency load utilized in the test operation of radio transmitters.

When dummy loads are employed to test radio transmitters, it is essential to provide an adequate means for dissipating heat generated by the passage of current through the load. Various means have been utilized in the past to dissipate such heat, including liquid cooled devices, however, the prior art has not provided sufficiently rapid and efficient heat transfer.

Accordingly, it is an object of the present invention to provide an improved heat dissipating system.

It is another object of the present invention to provide an improved system for moving cooling fluid past a heater element.

It is still another object of this invention to provide a system for dissipating heat generated by the passage of current through resistive elements in a load.

A dummy load for testing radio transmitters may include a plurality of resistive elements connected in series. According to the invention, the elements are vertically arranged within glass tubes supplied with liquid for cooling purposes. Vents at the top of the tubes provide for the escape of vapor produced by the heated resistors. Within the tubes, and enclosing the resistors, are suitably mounted sleeves connected to allow fluid to pass through the space between the resistors and the interior walls of the sleeves. The steam produced by the heated resistors within the sleeves induces a siphon effect which pulls the water upwardly through the passages between the resistors and sleeves in a rapid manner, thus providing a high rate of heat transfer to quickly and efficiently cool the load.

Other objects of the invention will be apparent from the following detailed description with reference to the accompanying drawings, which, by way of illustration, show a preferred embodiment of the invention and what is now considered to be the best mode of applying the principles thereof.

In the drawings:

FIG. 1 is a perspective view of a transmitter dummy load and the heat dissipating system of this invention;

FIG. 2 is a sectional view of a resistor and heat transfer unit;

FIG. 3 is a sectional view taken along line 3—3 of FIG. 2; and

FIG. 4 is a schematic showing the electrical circuit for FIG. 1.

Referring in detail to the drawings, wherein similar reference numerals identify corresponding parts throughout the several views, a transmitter 12 is electrically connected to the ends 14 and 16 of a series connected dummy load line 19 (see FIGS. 1 and 4). The load line includes pluralities of resistors 20 and 22 connected in series by a balanced two wire transmission line 18. The resistors may be tapered in resistance value to obtain equal amounts of power dissipation in each pair.

A plurality of cylindrical, vertically disposed glass tubes 24 enclose the portions of dummy load line 19 which include the series connected, cylindrically shaped resistors 20 and 22. Tubes 24 may be made of a commercially available glass sold under the trade name Pyrex. Ends 14 and 16 of transmission line 18 pass into lower exten-

2

sions 26 extending transversely near the bottom of the first pair of tubes 24 through water tight plugs 28. The bottom of each tube 24 is connected through water supply conduit 32 (FIG. 1) to a main water supply tank 34. The water level in the tank is high relative to tubes 24 to provide a gravity feed, and a valve 36 enables an individual to control the amount of water entering tubes 24. The resistors 20 are centered within respective vertical tubes 24 at approximately the mid portions thereof (see FIGS. 2 and 3). A glass sleeve 38 is mounted concentrically about resistor 20. Sleeve 38 is held in place by three tabs 40 at both the bottom and top of the sleeve. The tabs may be made of a commercially available plastic sold under the trade name Teflon and are secured to resistor 20 by screws 42 and co-operating nuts 44. Six strap connectors 46 at both the top and bottom of resistor 20 provide electrical and mechanical connections between the resistor and a pair of elbow connectors 48. Connectors 46 are secured to the resistor and elbow connectors by screws 50 and nuts 52. Elbow connectors 48 include a cylinder 54 press fit to flanged disc 56, which, in turn, is secured to a plug element 58 by a screw 60. An elbow 62, into which plug 58 is pressed, is frictionally secured to transmission line 18 to complete the link.

Thus, an electrical and mechanical connection is provided between the sections of transmission line 18 and the connecting resistors 20. The transmission line provides the connection between each vertical tube, passing through water tight plugs 28 in lower extensions 26 and upper extensions 29. A bus connector 64, connected to the ends of each of the two parallel lines of vertical tubes 24, provides an electrical connection between the string of series connected resistors 20 and the string of series connected resistors 22 to thereby form the series connected dummy load line 19.

The top end 66 (FIG. 1) of each vertical tube 24 is connected through a conduit 68 to a steam condenser 70, thereby providing fluid communication between each tube and the condenser. For the sake of expediency, FIG. 1 only shows one tube connected to tank 34 and condenser 70, however, in practice all of the tubes are similarly connected, although, if desired, each tube may have a separate tank and condenser for individual control purposes.

In operation, prior to actuation of the transmitter, valve 36 is opened and water from main supply water tank 34 flows into each vertical tube 24 to a level above resistors 20. Because the water supply flow is gravity controlled, the water level in the main supply water tank will be at the same level as the water level in the tubes. The water enters the tubes through conduits 32 covering glass sleeves 38 and the space between the sleeves and resistors. Thus, a relatively small portion of the total amount of water within each vertical tube is partially separated from the main body of water by the sleeve. This allows that portion of the water to reach the boiling point before the bulk of the liquid within the tube. As the temperature of the load increases, the portion of water within the sleeve is heated and converted to steam. The steam, since it is less dense than water, rises rapidly in the space between the resistor and the sleeve, and passes through top 66 of the tube and condenser conduit 68 to steam condenser 70, which converts the steam into water. The hot water within the space adjacent the resistor also rises upwardly but at a slower pace than the steam. The result is a convection flow in the tube, with hot water and steam passing through the top, and cooler water coming in at the bottom.

The steam produced adjacent the resistor expands outwardly but can only go as far as the glass sleeve. Thus, the pockets of expanding vapor and steam strike the glass sleeve and rebound toward the resistor. This ac-

tion produces a high degree of fluid turbulence about the resistor, thereby producing a rapid and efficient transfer of heat from the resistor to the surrounding medium.

Thus, an efficient system has been provided for the rapid transfer of heat from elements such as resistors which generate great quantities of heat. By providing a sleeve adjacent the resistor, the heat is localized within the tube between the resistor and the sleeve. This enables rapid heating of the portion of the water between the resistor and sleeve, thereby quickly converting the water into steam and providing a more rapid flow of fluid past the resistor for more efficient heat dissipation. The system herein disclosed also enables heater elements which supply relatively little heat, to increase the flow of fluid past the resistor element, by producing steam in a localized section resulting in more efficient heat dissipation.

While a specific embodiment of this invention has been shown and described in detail to illustrate the application of the inventive principles, it should be understood that the invention may be embodied otherwise without departing from such principles, and should not be limited except as defined in the following claims.

What is claimed is:

1. A heat transfer system, comprising means for radiating heat, a vertically extending sleeve open at both ends spaced from and encircling said heat radiating means, a container spaced from and encompassing said heat radiating means and sleeve, means for supplying liquid to said container, said sleeve and said heat radiating means defining a space therebetween in liquid connection at the upper and lower ends of said sleeve with said container, whereby heat radiated from said heat radiating means changes liquid, supplied to said space into gas, thus creating a fluid flow past said heater means.

2. A system for dissipating heat produced by a dummy load for an electrical transmitter, comprising a two wire transmission line connected across the output of an electrical energy transmitter, a plurality of resistive elements connected in series by said transmission line, means for enclosing said resistive elements, said enclosing means including vertical outer tubes having steam exits at the top portions thereof and liquid intakes at the bottom portions thereof, each of said vertical tubes including therein a concentrically mounted sleeve, said sleeve having openings at the bottom and top thereof, communicating with the corresponding one of said outer tubes, one of said resistive elements being positioned within each of the sleeves whereby the heat which radiates from said resistive elements heats the liquid supplied to the enclosing means converting the liquid adjacent the resistive elements to steam to initiate a rapid and efficient flow of fluid past said resistive elements.

3. A heat transfer system for a dummy load utilized with an electrical energy transmitter, comprising a plurality of resistive elements, a plurality of vertical sleeves each open at both ends and surrounding and spaced from a respective one of said resistive elements, a plurality of tubular members each enclosing a respective one of said resistive elements and the corresponding sleeve, means supplying liquid to each of said tubular members to a

level above the tops of said sleeves, and means allowing the escape of vapor from each of said tubular members, whereby the heat from said resistive elements changes some of the liquid supplied to each of said tubular members into vapor and produces a fluid flow that transfers heat from said resistive elements.

4. A heat transfer system according to claim 3, wherein each of said tubular members includes an upright tube having a pair of transmission line ports.

5. A heat transfer system according to claim 3, wherein said liquid supplying means includes a liquid supply tank and conduits providing liquid communication between said tank and tubular members, and said vapor escape means includes a steam condenser and steam condenser conduits providing fluid communications between the top of said tubular members and said steam condenser.

6. A heat transfer system comprising an electrical energy transmitter, a dummy load connected across the output of said transmitter, said dummy load including a plurality of resistive elements, a transmission line, and means connecting the resistive elements to the transmission line, said connecting means including a plurality of conductive straps connected to each end of each resistive

25 element, a connecting elbow providing an electrical connection between the straps at each end of each resistive element and the transmission line, an open ended cylindrical glass sleeve spaced from and encompassing each of said resistive elements, a plurality of tabs connected to each end of each resistive element for supporting the corresponding glass sleeve in a vertical position, a plurality of cylindrical glass tubes, each of said glass tubes enclosing one of said glass sleeves and the associated resistive element and connecting straps and elbows, a water

30 supply tank, a conduit and conduit control valve providing liquid communication between said water supply tank and said glass tube through an opening in the bottom of the tube, a steam condenser, a conduit providing fluid communication between said steam condenser and said tubes through openings in the tops of said tubes, a pair of integrally formed extensions projecting outwardly perpendicular to each tube near the bottom and top thereof, said transmission line extending through each of said extensions to connect to the corresponding elbows, whereby the actuation of the transmitter sends electrical energy through the dummy load heating the resistive elements and converting some of the water within the space between the resistive elements and the glass sleeves into vapor, to dissipate heat generated by said resistive elements.
